UNITED STATES PATENT OFFICE.

RALPH R. RICHARDSON, OF CHICAGO, ILLINOIS, ASSIGNOR TO CHICAGO CARTON COMPANY, OF CHICAGO, ILLINOIS, A CORPORATION OF ILLINOIS.

CARTON.

1,126,279.

Specification of Letters Patent.

Patented Jan. 26, 1915.

Application filed April 5, 1913. Serial No. 759,011.

To all whom it may concern:

Be it known that I, RALPH R. RICHARDSON, a citizen of the United States, and a resident of Chicago, in the county of Cook and State of Illinois, have invented certain new and useful Improvements in Cartons; and I do hereby declare that the following is a full, clear, and exact description thereof, reference being had to the accompanying drawings, and to the letters of reference marked thereon, which form a part of this specification.

This invention relates to an improved carton for crackers, biscuits and like articles of merchandise of that kind consisting of a single piece or blank of paper or fiber-board, provided with flaps and adapted to be folded to form the body of the carton, and a flexible lining sheet of paraffined or water proof paper, which is interfolded with the blank which forms the inclosure, and is designed to protect the contents of the carton from access of moisture thereto.

The invention consists in the matters hereinafter pointed out and set forth in the appended claims.

In the accompanying drawings—Figure 1 is a face view of the end portion of the blank which forms the body of the carton; Fig. 2 is a perspective view of one end of the blank and lining sheet, when the front and rear walls of the blanks are folded at right angles to its bottom wall, and its end flaps are unfolded; Fig. 3 is a perspective view of the same parts, with the end flaps on the front wall, with the associated portion of the lining sheet folded inwardly; Fig. 4 is a like perspective view, showing the end flaps on both the front and rear walls of the carton after being folded inwardly, with the end flap on the bottom wall still unfolded; Fig. 5 is a perspective view of the end of the carton, with all of its end flaps folded inwardly to form the complete end wall of the carton; Fig. 6 is a horizontal section taken through the infolded end flaps of the carton, with the adjacent parts of the lining sheet, taken on line 6—6 of Fig. 5.

As shown in said drawings, the sheet or blank (Fig. 1) from which the carton is formed embraces four connected sections A, B, C and D, which are joined to each other along longitudinal parallel folding lines 1, 2 and 3, and of which the section A forms the front wall, the section B, the bottom wall,

the section D the rear wall, and the section E, the top wall of the completed carton. The section D is provided with a marginal flap D', which overlaps the top of the front wall when the carton is filled and closed. 60 The ends of the sections A, B and C are provided with extensions, constituting flaps A', B' and C' which, when folded together, form the end wall of the carton. The upper edges of the end flaps A' and C' are preferably in 65 alinement with the upper, longitudinal margins of the front-wall and rear-wall sections A and C, while the bottom margins a and c of said end flaps are preferably inclined upwardly toward the free ends of said flaps. 70 The end flap C' is shown as provided on its upper margin with a laterally or upwardly projecting flap-C², which is folded inwardly over the open top of the body of the carton, as common in cartons of this general character. The flap B' on the bottom B is preferably tapered on its side edges. In the interfolding of the said end flaps, to form the end wall of the carton, the front-wall and rear-wall flaps A' and C' are first folded in 75 overlapping relation, and the bottom-wall flap B' is then folded upwardly outside of the said flaps A' and C'. When the said end flaps are thus interfolded, the same are secured together by a fastening device passing 80 through the same; such fastening device, as shown, consisting of a metal staple F.

The lining sheet G of paraffined paper or the like, is made approximately the same in external dimensions as the connected sections of the carton with their end flaps. The said lining sheet is applied to, or against the inner surfaces of the carton sections A, B and C, with its lateral marginal part adjacent to the end flaps, A', B' and C', and 85 interfolded with the latter. The said lateral, marginal part of the lining sheet is so interfolded with the end flaps, that one infolded part of said sheet rests against and covers the inner face of the completed end wall, 90 another part of said lining sheet is located between the innermost and intermediate end flaps, while another part of said lining sheet is located between the intermediate and external end flaps. The fastener F, by which the said end flaps are secured together, passes, or is inserted, through the marginal part of the lining sheet, which is folded between the innermost and intermediate flaps, 95 so that this portion of said lining sheet is 100

confined in place by said fastener; the portion of the lining sheet which rests within and covers the inner face of the end wall being left free or unattached to said end wall, 5 except so far as it is held or confined at its margins by the interfolded end flaps.

Figs. 2, 3, 4 and 5 of the drawings illustrate the manner in which the end flaps and the adjacent marginal portion of the lining sheet 10 may be interfolded. As shown in Fig. 2, the front and rear walls or sections of the carton have been bent upwardly at right angles to its bottom wall, the end flaps of the carton are in extended position and the lining sheet rests in place with its front and rear margins extending upwardly in the plane of, and above the front and rear walls or sections of the carton. The parts being in 15 the position described, the front-wall flap A' is folded inwardly to the position shown in Fig. 3, carrying with it the marginal part G' of the lining sheet beneath it. When the part G' is thus folded inwardly, an oblique fold g is formed by the folding upon itself 20 of the part G² of the lining sheet, which rests upon the bottom-wall flap B'. The rear-wall flap C' is then folded inwardly, as seen in Fig. 4, thereby carrying or folding the portion G³ of the lining sheet, inwardly 25 against the outer face of the front-wall flap A'. As the part G' of the lining sheet is thus folded inwardly, the part G² of said lining sheet is again folded upon itself, on a second oblique folding line g'. At the 30 completion of this second fold, the part G² of the lining sheet is folded into the form of a triangular tongue or flap, as shown in Fig. 4, which flap projects outwardly from beneath the lower edge of the flap C' 35 and rests on the flap B'. The said flap B' is then folded upwardly against the flap C', and the triangular folded part G² of the lining sheet, is thereby folded between said flaps B' and C'. The metal fastener is then 40 inserted through the flaps and the part G³ of the lining sheet (Fig. 6), thereby securing these parts together.

By reason of the interfolding of the triangularly folded part G² with or between 45 the flaps C' and B', or intermediate and outer flaps, the lower margin of the inner marginal part G' of the lining sheet is so firmly confined or held in place, that it will not be displaced during the operation of 50 filling the carton or inserting the contents of the same. It being understood that the marginal part G³ of the lining sheet is secured between the innermost and intermediate flaps A' and C', by the fastener F, 55 while the marginal part G' of said lining sheet is secured or confined at its lower margin, or along the lower margins of the said innermost and intermediate flaps A' and C', in the manner described, it follows that 60 65 when the body of the carton is set up and

in readiness for filling, the lining sheet will be firmly held or confined at both ends of the carton, so that it cannot be displaced in handling the carton, or by any force that it may be necessary to apply to the lining sheet during the filling operation. After 70 the carton and its lining have been set up, the end flaps secured, as shown in Fig. 5, and the contents of the carton inserted therein, the upper margins of the lining sheet at the front, rear and ends of the carton, will be folded inwardly or downwardly 75 to completely inclose or surround the contents, as heretofore common in the case of cartons provided with such lining sheets. 80

It is to be understood that so far as the desired effect of holding or confining the lining in place in the carton is concerned, it is not necessary that the end flaps and associated parts of the lining sheet be folded 85 in the particular manner or order stated; the principal feature of my invention, being the interfolding of parts of the lining sheet between the three end flaps, which are secured together by a fastener extending 90 through the same, while the part of the lining sheet which is inside of the completed end wall is left unperforated, and is held in place by the interfolding of the adjacent parts of the said sheet between said end flaps. Moreover, instead of the fastener consisting of a metal staple, any other form of fastening device may be used, which is adapted for insertion through, and to firmly join, the end flaps and the portion of the lining sheet interposed between said end flaps. 95

A carton made as hereinbefore set forth not only has the advantage described, so far as the holding in place of the lining sheet is concerned, but it has the further advantage 100 that the metal fastener used for rigidly connecting the end flaps is covered or protected by the inner fold of the lining sheet; and cannot, therefore, come in contact with the contents of the carton. 110

From the foregoing description of a carton embodying my invention, it will be understood that the desired result will be obtained by such interfolding of the end or marginal parts of the lining sheet with the 115 three end flaps on the carton walls, that a single thickness of the lining sheet will rest against and cover the inner surface of the end wall formed by the infolded flap, another single thickness of said lining sheet 120 will be located between the innermost flap and the intermediate flap that is folded inwardly against the same, while a folded portion of the said lining sheet will be folded between the said intermediate flap and the outermost flap. Moreover, in connection 125 with the flaps and lining sheet, thus interfolded, the flaps are secured or united to each other by a fastener which is inserted through the same and passes through the 130

single thickness of the lining sheet which extends or is located between the innermost and intermediate flaps.

From what has been hereinbefore stated, 5 it will be understood that a carton embodying my invention may differ in its details from that shown in the drawings, and I do not, therefore, desire to be limited to the particular features of construction illustrated, except as pointed out in the appended claims.

I claim as my invention:

1. A carton, comprising a blank provided at its end with three flaps adapted to be folded in overlapping relation with each other, thereby forming the end wall of the carton, a lining sheet, one marginal portion thereof being folded inside of the innermost flap, another marginal portion being folded 10 between the innermost and intermediate flaps, and an intermediate portion folded upon itself and folded between the intermediate and outermost flaps, said intermediate portion of the lining sheet being joined to 15 the lower margins of said first mentioned portions of said lining sheet, and fastening means extending through the interfolded

flaps and said portion of the lining sheet between said innermost and intermediate flaps.

2. A carton, comprising a blank provided 30 at its end with two side flaps and an intermediate bottom flap adapted to be folded upon each other, and a lining sheet within said carton having its marginal portion in overlapping engagement with said flaps, a 35 portion of said sheet in engagement with one of said side flaps being folded inside of the innermost flap, the other portion folded between said side flaps, and the portion in engagement with the bottom flap being folded 40 upon itself and folded between the outer side flap and said bottom flap, its lower margins being joined with the first mentioned portions of said sheet, and a staple inserted through said flaps and the portion of the 45 lining sheet between the side flaps.

In testimony, that I claim the foregoing as my invention I affix my signature in the presence of two witnesses, this 20th day of March A. D. 1913.

RALPH R. RICHARDSON.
